UNITED STATES PATENT OFFICE.

JULIUS S. MEYER, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 13,383, dated October 31, 1882.

Application filed August 11, 1882. Term of patent 3½ years.

To all whom it may concern:

Be it known that I, JULIUS S. MEYER, of New York, in the State of New York, have invented a new and original Design for Carpets, 5 of which the following is a specification.

This invention relates to a new and original design for carpets and similar fabrics; and it consists in the novel grouping and configuration of figures hereinafter more fully described.

10 The accompanying photograph illustrates a face view of a carpet having my new design.

The design consists of a number of panels overlapping one another at their edges and corners irregularly, each ornamented by loosely-disposed flower and leaf groups, resting, in

15 the case of some of the panels, on a blank field,

and in the case of others of the panels in a figured field. The panels are irregular in shape, though entirely right-lined, and are bounded by various borders of various widths 20 and ornamentations, with two or three smaller square panels at the corners of the larger panels, all of which is fully and clearly shown in the accompanying photograph.

I claim—

25 The design for carpets, consisting of the panelled design, substantially as shown and described.

JULIUS S. MEYER.
